UNITED STATES PATENT OFFICE.

WESLEY E. LAIRD, OF PITTSFIELD, MASSACHUSETTS, ASSIGNOR TO GENERAL ELECTRIC COMPANY, A CORPORATION OF NEW YORK.

ABRADING DEVICE.

1,396,585.

Specification of Letters Patent.

Patented Nov. 8, 1921.

Application filed March 21, 1919. Serial No. 284,071.

To all whom it may concern:

Be it known that I, WESLEY E. LAIRD, a citizen of the United States, residing at Pittsfield, in the county of Berkshire, State 5 of Massachusetts, have invented certain new and useful Improvements in Abrading Devices, of which the following is a specification.

The present invention comprises an apparatus 10 for cleaning the surface of sheet metal, particularly the edges, preparatory for welding, or any other desired purpose.

When sheets of metal are welded to each other it is desirable to remove surface 15 oxid and scale from the parts to be welded to bring clean metal surfaces into direct contact. The apparatus described herein is particularly adapted to remove the surface layer from the edges of metal sheets preparatory to producing a seam weld not substantially greater in thickness than the rest 20 of the sheet metal. The novel features of my invention will be pointed out with particularity in the appended claims.

25 The following description is to be taken in connection with the appended drawings in which Figure 1 is a top view of an apparatus embodying my invention; Fig. 2 is a side elevation; Fig. 3 is a side elevation 30 taken at right angles to Fig. 2; Fig. 4 illustrates a preferred form of abrading device and Fig. 5 illustrates smoothing rolls engaging the edges of sheet metal in one form of my invention.

35 The apparatus embodying my invention comprises a framework 1 consisting of upright and transverse members best shown in Fig. 2. The horizontal bars 2, 2' and the connecting strips 3 (Fig. 1) constitute a 40 table or platform for the reception of a sheet 4. For convenience of working, a pack of sheets 5 (Fig. 2) may be placed by a crane or other convenient means on a bridge 6 which overhangs the platform. The 45 bridge 6 has not been shown in Fig. 1 as it would hide other parts of the apparatus but the broken brackets indicate the location of the support 6 in Fig. 1. Individual sheets are pulled from this pack upon the shelves 50 7, 7' and then placed by the operator upon the table in a flexed position with the edges

inserted in the guides 8, 9, located on opposite edges of the frame-work. The sheet is inserted beneath the presser bars 10, 11, supported by the brackets 12, 12', which are in 55 turn carried by the cross bar 13. The bars 10, 11 hold the sheet 4 in position to be engaged by projecting lugs 14 on the chain 15. Four sets of chains 15 are provided, each passing over sprocket wheels 16 mounted on the shafts 17, 18, which are in turn driven by a motor 19 through suitable worm 20 upon the shaft 21, engaging with a gear 22 on the shaft 17. The travel of the chains. 25 thus propels the sheet over the platform, 60 the flexed position of the sheet pressing the edges outwardly into contact with the lateral guides 8, 9, and causing it to be pressed into contact with abrading devices which 65 grind the surfaces of a strip along the respective edges of the sheet. As best shown in Fig. 4, the particular form of abrading devices illustrated in the drawing comprise 70 belts 23, 24 and 23', 24' surfaced with abrasive material, such as emery. The belts 23, 75 24 pass respectively over paired pulleys 25, 26 and 27, 28 driven by belt 29 from the motor shaft 21 as best shown in Fig. 1. The belt 29, for example, passes under a pulley 30 mounted on a common shaft 31 with the 80 pulley 25 and passes over a pulley 32 mounted on a shaft 33 in common with the pulley 27 to rotate in opposite directions and driving the belts 23, 24 as indicated by arrows 85 in Fig. 4 in opposite directions, in each case toward the outer edge of the sheet so as to exert traction to hold the sheet in place while cleaning the surface. The belt 29 is held in frictional engagement with the pulleys 30, 32 by a tightener 34. The tension 90 of the abrading belts 23, 24 may be varied by adjusting the position of the blocks 35, 36 on the supporting arms 37, 38, by means of suitable screws 39. The arms 37, 38 may be held fixedly in a desired position by thumb 95 screws 40 engaging with an upright member 41 constituting part of the frame of the apparatus. The driving members for the abrading belts on the opposite side of the apparatus are similarly arranged, the belt 100 42 being crossed to reverse the rotation of the belts 23', 24' so as to cause them to move

from the center toward the edge of metal sheet 4. Although I have shown a preferred form of abrading device in the illustrated embodiment of my invention, I desire it to be understood that various modifications may be used advantageously in some cases depending on the character of the work. In some cases it may be desirable to use but one of the abrading belts or their 10 equivalent to grind sheets upon one side only.

In some cases it is desirable to provide pressure rolls engaging with the edges of the sheets to smooth out irregularities. As 15 shown in Fig. 5 the rolls 44, 45 engage the sheet 4 between them, the roll 45 being mounted on a shaft 46 driven by a chain 47 engaging with sprocket wheels 48, 49 mounted respectively on the shafts 46 and 47. The 20 roll 44 is mounted directly on the upright 41 of the frame of the apparatus.

After the sheets 4 have been propelled past the abrading devices they are shoved over the horizontal guides 50 and piled in 25 a stack at the end of the apparatus. The guides 51, 52 located at the extremities of the sheets hold up the edges of the sheets until the center has begun to fall so as to obviate damage to the corners. The up- 30 right post 53 prevents displacement of the sheets and enables them to be piled one above the other in a pack so as to be readily picked up by a crane or handle or in any other desired manner.

35 What I claim as new and desire to secure by Letters Patent of the United States, is:—

1. An abrading apparatus comprising means for holding sheet metal in a flexed position, an abrading device acting on an 40 edge of said sheet and means for causing relative traversing motion between said sheet and said abrading device.

2. An abrading apparatus comprising a framework having a platform, guides 45 spaced apart on said platform and adapted to receive the edges of sheet metal while in a flexed position, paired abrading devices acting upon opposite sides of said sheet metal, and means for traversing said sheet 50 metal with respect to said abrading devices.

3. An abrading apparatus comprising a framework having parallel guides spaced apart, means for propelling sheet material over said framework with edges in contact 55 with said guides, and abrasive means positioned to engage with a predetermined part of the sheet material propelled over said framework while the edges of the sheet material are held in position by said guides.

60 4. An abrading apparatus comprising a framework having parallel guides spaced apart, means for propelling sheet material over said framework with edges in engagement with said guides, and a revolving abrasive device mounted on said framework in 65

position to abrade the edges of said sheets while the sheets are held in position by said guides.

5. An abrading apparatus comprising a framework, belts surfaced with abrading material rotatable supports therefor mounted on said framework, means for driving said belts in opposite direction and means for propelling sheet metal over said framework with the edge thereof in contact with 75 the abrading surfaces of said belts.

6. An apparatus for abrading the edges of sheets of material, comprising guiding means adapted to determine the path of travel of each sheet through the apparatus, 80 a pair of adjacent traveling belts arranged transversely of the path of travel to the sheets provided with abrading surfaces respectively arranged in position to abrade top and bottom surfaces near an edge of 85 each sheet.

7. An abrading apparatus, comprising a pair of adjacent traveling belts provided with abrading surfaces, respectively arranged in position to abrade top and bottom 90 surfaces at the edge of an article to be abraded, said belts being arranged transversely to the edge of the article to be abraded and driven in the proper directions to exert traction on said article to hold it 95 against said abrading surfaces.

8. An abrading apparatus for sheets of flexible material, comprising guiding means for the edges of said sheets located so as to require said sheets to take a flexed position 100 in passing through said apparatus, whereby the edges of said sheets are forced against said guiding means, and means for simultaneously abrading top and bottom surfaces of two edges of said sheets, comprising a 105 pair of traveling abrading belts, located adjacent each of said edges, said belts being driven in the proper directions to exert traction on said sheets to hold the sheets against said abrading surfaces and in line with said 110 guiding means.

9. An abrading apparatus for sheets of flexible material adapted to be passed through said apparatus, comprising guiding means for the edges of said sheets located to 115 require said sheets to take a flexed position in passing through said apparatus whereby the edges of said sheets are forced against said guiding means, and means adapted to press upon said sheets at points between 120 the center and edges thereof so that the portions of the sheets between said pressing means and said guiding means are substantially flat and means for abrading an edge of said sheet as it passes through said apparatus.

10. An apparatus for enabling operations to be readily performed upon definite parts of the surfaces of sheets of flexible material, adapted to be passed through said appara- 125

tus, comprising guiding means for the edges of said sheets, located to require said sheets to take a flexed position in passing through said apparatus whereby the edges of said sheets are forced against said guiding means, and means adapted to press upon said sheets at points between the center and edges thereof, so that the portions of the

sheets between said pressing means and said guiding means are substantially flat, whereby a series of similar sheets passed through the machine will have their path of travel definitely determined. 10

In witness whereof, I have hereunto set my hand this 18th day of March, 1919.

WESLEY E. LAIRD.
